EXPLOSION PROOF PLUG AND SOCKET

John G. Howard and Philip S. Rockwell, Chicago,
Ill., assignors to The Pyle-National Company,
Chicago, Ill., a corporation of New Jersey

Application September 16, 1949, Serial No. 116,025

6 Claims. (Cl. 173—328)

1

This invention relates generally to an electric plug and socket structure and more particularly relates to a so-called explosion-proof fitting incorporating a novel delayed action structure therein whereby a momentary time delay may be manually introduced into the manipulation of telescopically related plug and socket elements.

According to the general features of the present invention, a plug member is provided which is movable axially rectilinearly out of a socket member having terminals situated at the end of arc-tight passages. The socket member carries a stop element which, in one preferred embodiment, takes the form of a ring which may be slidably mounted on the socket member and movable on a substantially lateral or radial plane relative to the axis of the plug and socket members. The plug member is provided with suitable flat or slotted portions to define shoulders that cooperate with the stop member and prevent axial withdrawing movement of the plug member after the terminals are separated and before the plug and socket members are separated. The stop member can then be moved laterally or radially, whereupon further straight-line withdrawal of the plug member from the socket member may be permitted. Polarizing means may be provided between the plug and socket members to maintain these elements in a predetermined alignment.

Most explosion-proof plug and socket structures heretofore provided have been constructed in accordance with designs which necessitate the employment of a rotatable locking member or zig-zag detent means requiring twisting or relative rotative motion between plug and socket components in order that a suitable time delay be provided for rendering the plug and socket fitting explosion-proof.

An object of the present invention is therefore, to provide an electric plug and socket adapted for use in hazardous locations wherein all necessity for relative rotative motion between the plug and socket components is completely eliminated.

A further object of the present invention is to provide an electric plug and socket structure suitable for use in hazardous locations whereby a suitable time delay for rendering the plug and socket fitting explosion-proof may be accomplished by manual operation of a simple stop element movable in the fashion of a reciprocating plunger.

Many other features, advantages and additional objects of the present invention will become manifest to those versed in the art upon making reference to the detailed description which follows and the annexed sheets of drawings, in which a preferred embodiment of the present invention is shown.

2

On the drawings:

Figure 1 is a cross sectional view with parts in elevation and with parts broken away of an electric plug and socket according to the present invention;

Figure 2 is a cross sectional view with parts in elevation and with parts broken away taken on line II—II of Figure 1;

Figures 3 and 4 are fragmentary cross sectional views of the time delay mechanism incorporated in the electric plug and socket according to the present invention showing steps in a typical operational sequence; and

Figures 5 and 6 show the steps of a typical operational sequence of a modified electric plug and socket according to the present invention.

As shown on the drawings:

Referring to Figures 1 and 2, the electric plug and socket of the present invention is shown as including a socket member indicated generally by the reference numeral 10, a plug member indicated generally by the reference numeral 11 and a stop member 12 for stopping the axial withdrawing movement of the plug in a manner which will be described in further detail hereinafter.

The socket member 10 includes a generally tubular housing 13 which may be made of metal and which preferably defines a suitable bore with internal shoulders therein for seating a sub-assembly of electrical elements. It will be understood that the housing 13 may also be provided with suitable connection means on one end thereof for attachment to a junction box or other point of attachment as may be appropriate for various types of installations in hazardous environments likely to include dangerous quantities of explosive mixtures.

In this particular embodiment, a suitable plug-like receptacle 14 made of an electrically non-conductive material and being of a generally cylindrical form with an annular shoulder 14a on one end thereof may be positioned within the socket housing 13 and firmly aligned therein by means of the internal shoulder defined by the socket housing 13. A snap ring 16 may be provided to fit in a suitable indentation defined by the bore of the socket housing 13 to lock the receptacle 14 in place.

The receptacle 14 is provided with a plurality of radially spaced arc-tight passages indicated generally by the reference numeral 17. The arc-tight passages may be provided with a slight tapered counterbore at the ends thereof as at 17a so as to provide a finding area or locating area for male electrical elements. The arc-tight passages may be further counterbored internally to receive conventional female terminals 18 therein. Suitable end caps 19 may be provided for the terminals 18 in the form of reduced diameter

portions adapted to receive a receptacle cap 20 in fitted assembly thereon. The receptacle cap 20 is held on the receptacle 14 by means of a fastener 21.

One of the terminals 18 carried by the receptacle 14 may act as a ground terminal and therefore may be provided with a grounding wire 22 which is suitably connected to the socket housing 13 of the socket member 10. It will be understood that such ground connection may be effected in other conventional manners, for example, a spring wire attached to the terminal 19 may be arranged to contact the housing 13 at the locale between the shoulder portion 14a of the receptacle 14 and the housing 13.

The socket housing 13 may be provided with suitable means for retaining a sealing wax, or similar compound in the end thereof, for example, as shown in this particular embodiment, the socket housing 13 has an annular groove 23 formed therein so that the entire end of the socket housing may be filled with a sealing wax, thereby enclosing the exposed ends of the terminals. It will also be understood that suitable conductor leads may be provided and connected to each of the electric terminals 18 via the end caps 19.

The plug member 11 may be provided with an insulation shell 24 which is seated in one end of the plug member 11. A plug body 26 made of electrically non-conductive material is also provided having a cap portion 26a and in which may be firmly assembled a plurality of prong-like male electrical terminal elements indicated by the reference numeral 27.

It will be noted that one of the male terminals 27 may be of somewhat greater length than the others so as to serve the function of a ground terminal whereby the ground terminal will be the first to complete electrical contact and the last to break contact.

The plug body 26 may be provided with a shallow longitudinal groove 26b in order to seat a locating pin 28 which is operative to keep the plug body 26 from rotating within the plug member 11. Polarizing means may also be provided between the socket housing 13 and the receptacle 14.

The plug member 11 is provided with a generally tubular housing 29 which is preferably made of metal. As may clearly be seen on the drawings, the plug housing 29 may be provided with recessed flats formed on spaced diametrically opposed portions on its peripheral surface. Referring particularly to Figure 1, it will be noted that the lower portion of the plug housing 29 is provided with a rather lengthy flat indicated by the reference character 29a which is terminated at one end by an annular shoulder 30 and at the other end by a shoulder 35 defined by the normal peripheral portion of the plug housing which has not been removed to form the flat 29a.

On the other side of the shoulder 35, another flat 29b is defined which extends to the end of the plug housing 29.

Diametrically opposed from the shoulder 35 and flats 29a and 29b is an additional flat 29c. The flat 29c is of a limited length and terminates in shoulders defined by the normal peripheral portion of the tubular plug housing 29.

As will be evident in the operational description which is to follow, the location of the shoulder 35 and the flat portions 29a, 29b and 29c are all predetermined so that a definite fixed re-

lationship exists between the longitudinal or axial spacing of the various plug and socket components with respect to the axis of the plug member 11 and the socket member 10.

Referring now to Figures 1 and 2, the stop member 12 and its related elements may be described. The stop member 12 takes the general configuration of a ring with a central aperture 12a. A pair of projecting tabs 31 and 32 extend radially outward of the main body portion of the stop member 12. Each of the tabs 31 and 32 extends into the aperture 12a to form a flattened portion 31a and 32a, respectively, and is further provided with an appropriate slot 31b and 32b, respectively, through which may extend a shoulder head screw 33. A suitably aperture, flanged retaining ring 34 may be provided to snugly surround the end of the socket housing 13 of the socket member 10 and is arranged to cooperate with the shoulder head screws 33 to retain the stop member 12 in slidable relation with the socket member 10.

The tab 32 may be slightly longer than the tab 31 and may be bent over so as to provide a button-like operating portion as indicated at 32c.

If desired, appropriate bosses 36 may be provided on the stop member 12 and the socket housing 13 so as to seat a small resilient member such as a coil spring 37 therebetween. By virtue of such a provision, the stop member 12 may be normally biased towards an upper position.

Polarizing means may be provided between the socket member 10 and the plug member 11 so as to insure proper pre-alignment of the terminals 18 and 27 as well as to maintain alignment of the plug and socket members during relative movement thereof. In the present embodiment, the polarizing means takes the form of a bead and groove structure, a bead 38 being provided in the inside bore of the socket housing 13 and a co-operating groove 39 being formed longitudinally in the wall of the plug housing 29 (Figure 2).

When the plug member 11 is completely inserted in the socket member 10, the male terminals 27 are completely seated within the airtight passages 17 so that electrical contact is made along the entire length of the female terminals 18. In this position, the annular shoulder 30 may be snugly seated up against the retaining ring 34.

It may be noted that the plug member is not locked in closed contact position within the socket member and any extraordinary strain placed on a conductor leading to the plug member 11 will cause the plug member 11 to be partially withdrawn from the socket member 10, at least to the extent that the electrical terminals of the plug and socket members will be separated. It is desirable to provide this switching effect as a safety measure since it is quite possible that a small vehicle or a careless workman forcibly engaging and parting a conductor leading to an explosion-proof plug and socket as herein described would inadvertently create an explosion hazard if the electrical contacts were to remain joined and current flow was not interrupted to the conductor. It will be apparent that this feature also permits the structure to be employed as a switch.

Referring now particularly to Figures 1, 3 and 4, the operational sequence of a withdrawal movement will be described particularly with respect to how a momentary time delay may be manually introduced into the manipulation of the telescopically related plug and socket elements.

When the plug member 11 is fully inserted into the socket member 10, the stop member 12, being normally biased to an upper position by the resilient member or spring 37 has the flattened portion 31a of the tab 31 riding up against the flat 29a of the plug housing 29 or in near proximity thereto. Thus, when the plug member 11 is partially withdrawn to the position shown in Figure 1, the stop member 12 will engagingly abut the shoulder 35 which, in effect, rises up between the flat portions 29a and 29b of the plug housing 29. Further withdrawal movement of the plug member 11 is thereby precluded temporarily. It should be noted that, in this position, the terminals are separated but the plug terminals 27 have not left the arc-tight passages 17.

In order to permit the further withdrawal of plug member 11 from the socket member 10, the stop member 12 may be depressed against the bias of the resilient member or spring 37 so that the tab 31 of the stop member 12 will clear the shoulder 35. It should be noted that the movement of the stop member 12 is generally lateral or radial relative to the axis of the plug and socket members. In order that the movement of the stop member 12 be accommodated, the flattened portion 32a of the tab 32 formed on the top part of the stop ring 12 finds a clearance in the recess provided by the flattened portion 29c located diametrically opposite the shoulder 35.

Thus, after the stop member 12 is moved radially further withdrawal movement of the plug member 11 is permitted, as shown in Figure 3, until such time as the flattened portion 32a of the tab 32 on the stop member 12 engages the shoulder presented by the terminating portion of the flattened portion 29c.

In order to again permit further withdrawal movement of the plug member 11 from the socket member 10, the stop member 12 must be released so that the flattened portion 31a of the tab 31 on the bottom portion of the stop ring 12 may again move upwardly toward the flattened portion 29b of the plug housing 29 and the flattened portion 32a of the tab 32 on the upper portion of the stop ring 12 will clear the shoulder presented by the end of the flattened portion 29c, thereby permitting complete withdrawal of the plug member 11 from the socket member 10. This phase of operation is shown in Figure 4.

It will be understood that any arc or flame drawn between the terminals 18 and 27 will be cooled below ignition temperatures before the plug terminals 27 leave the arc-tight passages 17.

Attention is invited to the fact that a particularly advantageous feature of the arrangement just described lies in the fact that all necessity for producing a relative rotative motion between plug and socket components as has been necessary in most explosion-proof plug and socket fittings heretofore provided has been completely eliminated and a suitable time delay for rendering the plug and socket fitting explosion-proof is accomplished merely by a simple manual actuation of a plunger-like stop member.

Referring now to Figures 5 and 6 a slightly modified form of an electric plug and socket incorporating the principles of the present invention is shown in two positions of a typical withdrawal sequence. In this form, the plug housing 29' is provided with a flat portion as at 40 which differs from the flat portions 29a and 29b provided on the plug housing 29 in that no

separate shoulder 35 is provided but the flat portion 40 is medially spaced so as to terminate near the open end of the plug housing 29' in a shoulder 41 presented by the normal peripheral wall portion of the generally tubular plug housing.

Located diametrically opposite the flattened portion 40 and the shoulder 41 is a flattened portion 42 which, unlike the flattened portion 29c, does not take the form of a slot-like flat, but extends completely to the open end of the plug housing 29'.

The remainder of the plug and socket structure shown in Figures 5 and 6 is exactly similar to that provided in Figures 1, 2, 3 and 4 and corresponding reference numerals have been provided for the sake of orientation.

In effecting a withdrawal movement of the modified fitting the stop member 12' will engage the shoulder 41 when the plug member 11' is partially withdrawn from the socket member 10' so that the terminals are separated but the plug terminals 27' are still within the arc-tight passages 17'. The stop member 12' is then depressed into the recess presented by the flattened portion 42 so as to clear the shoulder 41 and further withdrawal movement is permitted as shown in Figure 6.

It will be evident that the principles of this invention may be incorporated into other design applications than those herein illustrated by way of preferred embodiment. For example, the shoulder 35 and the corresponding diametrically opposed flat 29c may be duplicated at spaced intervals along the length of the plug member 11 so as to comprise a plurality of shoulders 35 and a plurality of corresponding diametrically opposed flats 29c. In this manner, the manual synchronization necessary to effect a withdrawal movement would result in the introduction of successive momentary time delays, the additive or cumulative effect of which may be desirable for the particular use to which electric plug and socket may be adapted.

It will be evident that we have described an improved electric plug and socket fitting incorporating a novel delayed action structure whereby a momentary time delay may be introduced manually into the manipulation of telescopically related plug and socket elements.

While a person skilled in the art might suggest various minor modifications to the structure herein described by way of preferred embodiment and illustrative example only, it should be understood that we do not propose to be limited to the precise details herein set out for the sake of clarity but wish to embrace within the scope of this patent all such modifications as reasonably and properly come within the scope of our invention.

We claim as our invention:

1. In an electric plug and socket apparatus, a socket member having passages formed therein, socket terminals in said passages, a plug member having plug terminals received in said passages and coacting with said socket terminals, said plug member being movable into and out of said socket member, latch means cooperating between said plug and socket members and including a movable stop member mounted on one of said members for movement relative to the other of said members, said stop member and said other of said members having a plurality of latch shoulders formed thereon, a first pair of said latch shoulders confronting one another for tempor- 70 rarily blocking the withdrawal of said plug mem-

ber after the plug and socket terminals are separated but before the plug terminals are withdrawn from said passages and a second pair of said latch shoulders confronting one another for temporarily blocking withdrawal of said plug member a second time after a further partial withdrawal from said socket member, said stop member being selectively actuated to relatively displace said latch shoulders out of blocking relation.

2. A plug and socket construction comprising, axially telescoping plug and socket members having coaxing terminals, a ring shaped stop member cooperating between said plug and socket members, guide means on the outermost of said plug and socket members confining said stop member for movement relative to the innermost of said members, said stop member and said innermost member having a plurality of latch shoulders formed thereon, a first pair of said latch shoulders confronting one another for temporarily blocking the axial separation of said plug and socket members after a partial separation, a second pair of said latch shoulders confronting one another for temporarily blocking the axial separation of said plug and socket members after a further partial separation, said stop member being selectively actuated to displace said latch shoulders relative to one another each time the separation of the plug and socket members is blocked.

3. A plug and socket construction comprising, axially telescoping plug and socket members having coaxing terminals, a ring shaped stop member cooperating between said plug and socket members, guide means on the outermost of said plug and socket members confining said stop member for movement relative to the innermost of said members, continuous biasing means between said outermost member and said stop member urging said stop member in one direction, said stop member and said innermost member having a plurality of stop shoulders formed thereon, a first pair of said shoulders confronting one another for temporarily blocking the axial movement of said plug and socket members after a partial separation, a second pair of said shoulders confronting one another for temporarily blocking the axial movement of said plug and socket members after a further partial separation, said stop member being moved against the biasing means to relatively displace said first shoulders out of confronting blocking relation and being moved by said biasing means upon release to relatively displace said second shoulders out of confronting blocking relation.

4. A plug and socket construction comprising, axially telescoping plug and socket members having coaxing terminals, a ring shaped stop member cooperating between said plug and socket members, guide means on the outermost of said plug and socket members confining said stop member for movement relative to the innermost of said members, continuous biasing means between said outermost member and said stop member urging said stop member in one direction, said stop member and said innermost member having a plurality of stop shoulders formed thereon, a first pair of said shoulders confronting one another for temporarily blocking the axial movement of said plug and socket members after a partial separation, a second pair of said shoulders confronting one another for temporarily blocking the axial movement of said plug and socket members after a further partial separation, said stop member being moved against the biasing means to relatively displace said first shoulders out of confronting blocking relation and being moved by said biasing means upon release to relatively displace said second shoulders out of confronting blocking relation.

members after a further partial separation, said stop member being moved against the biasing means to relatively displace said first shoulders out of confronting blocking relation and being moved by said biasing means upon release to relatively displace said second shoulders out of confronting blocking relation, said stop member having a bent over peripheral flange portion spaced radially outwardly of the outermost member and forming a manual actuating handle for moving said stop member against the biasing means.

5. A plug and socket construction comprising, axially telescoping plug and socket members having coaxing terminals, a ring shaped stop member cooperating between said plug and socket members, guide means on the outermost of said plug and socket members confining said stop member for movement relative to the innermost of said members, continuous biasing means between said outermost member and said stop member urging said stop member in one direction, said stop member and said innermost member having a plurality of stop shoulders formed thereon, a first pair of said shoulders confronting one another for temporarily blocking the axial movement of said plug and socket members after a partial separation, a second pair of said shoulders confronting one another for temporarily blocking the axial movement of said plug and socket members after a further partial separation, said stop member being moved against the biasing means to relatively displace said first shoulders out of confronting blocking relation and being moved by said biasing means upon release to relatively displace said second shoulders out of confronting blocking relation, said stop member having a bent over peripheral flange portion spaced radially outwardly of the outermost member and forming a manual actuating handle for moving said stop member against the biasing means, said biasing means more particularly comprising a coil spring bottomed on said flange portion and on said outermost member, respectively.

6. A retardation means for use with explosion proof separable plug and socket members comprising, a movable latch on one of said members and having two separate latch shoulders, and at least one additional latch shoulder on the other of said members, one pair of said latch shoulders confronting one another to block movement between said members after a first partial separation and another pair of said latch shoulders confronting one another to block movement between said members after a second partial separation, said latch being movable twice to effect complete separation of the plug and socket members.
